UNITED STATES PATENT OFFICE.

JOHN F. METTEN, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

SHIP PROPULSION.

1,245,486.

Specification of Letters Patent.

Patented Nov. 6, 1917.

Application filed November 17, 1914, Serial No. 872,512. Renewed July 10, 1917. Serial No. 179,767.

To all whom it may concern:

Be it known that I, JOHN F. METTEN, a citizen of the United States, residing at Philadelphia, in the county of Philadelphia 5 and State of Pennsylvania, have invented certain new and useful Improvements in Ship Propulsion, of which the following is a full, clear, and exact specification.

This invention relates to improvements in 10 turbine ship propulsion, and has particular reference to twin screw installations wherein the relatively high speeds of the turbine prime movers are lowered by reduction gearing interposed between each turbine and its propeller shaft.

Systems of this character are used in certain classes of relatively light and fast boats, such as torpedo boat destroyers, and it has been found desirable, owing to the construction 20 of these boats, to provide means whereby the twisting moments produced at the reduction gearing may be opposed to each other and thereby neutralized without being transmitted to the frame through the supports of either the turbines or the reduction 25 gearing. By means of this invention, not only are these objectionable twisting strains taken up in the gear casing, but they are thereby prevented from being transmitted to 30 the frame of the ship, so that a saving in weight is secured and also greater rigidity. This result is obtained independently of the direction of rotation of the propellers whether the ship is being driven forwardly 35 or rearwardly.

The invention, with reference to a preferred form thereof, will be more fully understood in connection with the description of the accompanying drawings, wherein—

40 Figure 1 is a plan view of an installation embodying the invention, and

Fig. 2 a vertical elevation.

1, 2 represent respectively port and starboard turbines having corresponding shafts 45 3, 4, supported at opposite ends in bearings 5, 7, and 6, 8, respectively. The bearings 7, 8 are provided with the usual thrust devices to hold the turbine elements in proper relative position, and are not necessary to be 50 shown in detail herein.

Each turbine comprises the usual lower casing portion attached to the ship, and a removable upper portion, and of course there may be suitable couplings, clutches or 55 the like, between each turbine and its pro-

peller. The reduction gearing for each turbine comprises a separate unit, consisting of heavy bases 9, 10, bolted to the floor plates 11, 12, which are supported by the transverse frame 14. On the bases 9, 10, respectively, 60 are carried the reduction gear lower casings 15, 16, having shafts 19, 20, journaled therein parallel to the shafts 3, 4, which are also journaled therein at each end of the lower gear casings 15, 16. The shafts 19, 20, respectively, are coupled to the propeller shafts 21, 22, and of course the bearings of shafts 19 and 20 will be provided with the usual thrust bearings to take the propeller thrusts in both directions of rotation. Within 65 each case 15, 16, and on the shafts 3, 19, and 4, 20, respectively, will be fastened the reduction gears 23, 24, 25, 26, as shown in dotted lines in Fig. 1, and proportioned so as to provide the desired reduction of speed 70 between shafts 3 and 21, and 4 and 22, respectively.

Owing to the reduction of speed, with consequent increase in torque, there will be very heavy twisting moments set up in the 80 gearing, which under ordinary practice would be transmitted through the bases 9, 10, respectively, to the floor plates 11, 12, and thence to frame cross members 14.

To withstand these strains, special heavy 85 construction both of the frames, flooring and fastenings would be required, but according to this invention, these strains being opposite to each other can be caused to neutralize each other by reason of the opposite rotation 90 of the two propellers without being transmitted to the cross frames 14 of the ship.

To accomplish this, each end of the bases 15, 16, is provided with deep horizontal struts as 31, 33, and 32, 34, respectively, 95 which touch each other and are bolted together at flanges 35, 36. The struts preferably extend at least to the line of centers through the shafts, as shown. These struts

31, 32, 33, 34, as seen from Fig. 2, are preferably integral with their respective bases 15, 16, and can be cast therein, being preferably hollow so as to save weight. 37, 38, are ordinary detachable covers for the gear elements, which can be removed when the 100 gears are to be inspected, without disturbing their bearings, the latter being entirely mounted on the bases 15, 16.

It will be seen that owing to these struts, the opposite twisting moments on each re- 110

duction gear will oppose and neutralize each other, independently of the floor fastenings, and independently of the particular directions of rotation of the propeller shafts 21, 5 22. Thereby, the rotational strains do not have to be taken up by specially heavy bases and specially heavy cross frames 14 as would otherwise be the case. These casings 15, 16, connected by struts as shown, practically 10 constitute a single self contained unit within which the opposing moments are completely neutralized.

The invention is not to be confined to the specific form and arrangement shown herein, 15 as it is susceptible of various modifications and changes within the scope of the appended claims without departing from the scope of the invention.

Having thus described my invention, I declare that what I claim as new and desire to secure by Letters Patent, is:—

1. In a twin screw ship propulsion system, the combination with two propeller shafts, of a pinion on the inner end of each shaft, 25 two bases each having bearings for one of said shafts at each side of the pinion and having laterally disposed corresponding bearings for a turbine shaft, a turbine shaft in each of said latter bearings, a 30 turbine on each shaft forward of said frame, a gear on each shaft between said bearings and meshing with the adjacent pinion, and connected struts carried by each base in line with corresponding propeller 35 shaft and turbine shaft bearings.

2. A reduction gear unit for twin screw ship propulsion system comprising a pair of separated bases each adapted to contain a driving shaft, a propeller shaft, and reduction gearing, and a transverse strut connecting said bases.

3. A reduction gear unit for twin screw ship propulsion system comprising a pair of separated bases each adapted to contain a driving shaft, a propeller shaft, and reduction gearing, and a separable transverse strut connecting said bases.

4. A reduction gear unit for twin screw ship propulsion system comprising a pair of separated bases each adapted to contain a driving shaft, a propeller shaft, and reduction gearing, and separable means rigidly connecting said bases.

5. In combination, a ship frame, two propellers, respective shafts therefor on respective sides of the ship frame, respective motors, reduction gearing between each motor and its propeller shaft, bearings for said gearing and a rigid frame carrying all said bearings, whereby the turning moments on said bearings will be balanced in said rigid frame for ordinary opposite driving torques on the propellers and not transmitted to the ship frame. 55 60

6. In combination, a ship frame, two propellers, respective shafts therefor on respective sides of the ship frame, respective motors, similar and opposite reduction gearing between each motor and its propeller shaft, bearings for said gearing and a rigid frame carrying said bearings, whereby the turning moments thereon will be balanced in the frame for ordinary opposite driving torques on the propellers and not transmitted to the ship frame. 65 70

7. In combination, a ship frame, two propellers, respective shafts therefor on respective sides of the ship frame, respective turbines, respective shafts for the turbines, a small gear on each turbine shaft, a respective large gear meshing therewith on each propeller shaft, bearings for all said shafts adjacent to said gears and a rigid frame carrying said bearings and absorbing and neutralizing the turning moments thereon 80 85 for ordinary opposite driving torques on the propellers.

8. In combination, a ship frame, two propellers, respective shafts therefor on respective sides of the ship frame, respective motors, reduction gearing between each motor and its propeller shaft, bearings for said gearing, two supporting members each carrying the bearings associated with a respective propeller shaft and means rigidly uniting said two supporting members so that the turning moments on the bearings for ordinary opposite driving torques on the propellers will be neutralized, and not transmitted to the ship frame. 90 95 100

In testimony whereof I affix my signature, in presence of two witnesses.

JOHN F. METTEN.
